UNITED STATES PATENT OFFICE.

GEORGE A. BEIDLER, OF OKLAHOMA, OKLAHOMA TERRITORY.

CAMPAIGN DEVICE.

No. 844,492.

Specification of Letters Patent.

Patented Feb. 19, 1907.

Application filed September 18, 1906. Serial No. 385,122.

To all whom it may concern:

Be it known that I, GEORGE A. BEIDLER, a citizen of the United States, residing at Oklahoma, in the county of Oklahoma and Territory of Oklahoma, have invented a new and useful Campaign Device, of which the following is a full, clear, and exact description, reference being had to the drawings hereto annexed.

10 The object of the invention is to produce a cheap, simple, and substantial device which while it will serve the purpose of a walking-cane may be used for creating enthusiasm, attracting attention, and furnishing amusement in parades, encampments, political or other meetings, and campaigns.

In carrying out the object stated the inventor has designed and constructed the body portion of the device to be used as a walking-cane and has adapted the same to contain articles of attraction, such as a banner-staff or flagstaff, which may be projected therefrom, as later shown. A wind-whistle is attached to the upper end of the cane in position to be sounded by blowing therein, and a mechanism is arranged at the bottom of the cane for firing percussion-caps or other explosives.

Referring to the drawings, Figure 1 is an elevation of the invention in its closed or compact form for use as a walking-cane. Fig. 2 is an elevation, on a smaller scale, showing a flagstaff and flag projecting from the cane at half mast. Fig. 3 is a like elevation showing the flag and staff at full mast. Fig. 4 is a separate elevation view of the flagstaff and flag. Figs. 5, 6, and 7 are perspective views, on larger scale, showing a closure for the opening through which the flagstaff is withdrawn from the cane. Fig. 8 is a sectional view, on same scale, of a wind-whistle at the end of the cane-handle. Fig. 9 is a sectional view of the device at the bottom of the cane for exploding caps. Fig. 10 is an elevation view showing an optional construction of a locking-stop required on the flagstaff.

Referring to the several figures, in all of which like characters of reference designate like parts, the cane 1, above mentioned, forms the body of the device and serves all the purposes for which a cane is used. This cane 1 is made hollow and is formed of any suitable sheet metal, and its upper end is formed into the usual semicircular handle 1^b. The flagstaff 2 is contained within the cane

1 and is removable therefrom through an opening 1^c at the upper end thereof. The staff 2 carries at one or both of its ends a flag or banner 3, which may be colored to represent a regular national flag, a candidate's picture, or other campaign attraction, and said flag or banner is wound closely around said staff in order to insert the latter into the cane.

65 The opening 1^c is provided with a closure 4 in the form of a slidable sleeve which embraces the handle of the cane 1 by friction. By sliding this sleeve or closure 4 upward, as shown in Fig. 6, the opening 1^c is uncovered, 70 and the staff 2 may be withdrawn therethrough and locked into either one of the positions shown in Figs. 2 and 3, the locking being accomplished by sliding the sleeve 4 downward until its slot 4^b straddles said staff just below one of the stops or balls 5 formed thereon, as shown in Fig. 7.

75 The staff 2 may be formed of any suitable material, such as tough wood or wire, and the locking-stops 5 for keeping the staff from sliding downward into the cane through the locking device 4 may be formed upon or secured to said staff in any suitable manner. In the present instance the staff 2 is made of wire, with the stops 5, molded around it, of 80 lead or other like material; but said stops may, if desired, be formed by closely coiling a small portion of said staff as shown in Fig. 10.

85 The wind-whistle 6 at the end of the handle 1^b is, as usual, formed of two sheet-metal disks 6^b and 6^c, placed with their concave faces together and having each a central opening 6^d, through which the air is forced to produce a whistling sound. The outer disk 90 or member 6^b is flanged, as at 6^e, to fit over and securely engage the flaring end of the handle 1^b and also acts to retain the inner disk 6^c in place.

95 The mechanism at the bottom of the cane 100 1 for exploding percussion-caps comprises the usual iron body 7 and has its upper end formed into a stud 7^b, extending securely up into the cane. The body 7 has the usual cap-recess 7^c, and the common firing-pin 8 is 105 arranged in said recess and extends down through the body for contact with the ground or pavement. The caps 9 or other explosives to be fired are placed in onto the head 8^b of the firing-pin 8, and when the lower end 110 of said pin is brought into forcible contact with any solid footing it strikes said cap 9

forcibly against the upper side of said recess and explodes it.

In the use of the improved device it may be used as a walking-cane or, as shown in Figs. 2 and 3, the staff 2 may be withdrawn to half or full mast and locked there for an additional attraction.

One idea in the use of the device is to equip an army of paraders, such as G. A. R. men or campaigners, with it, and while the staff 2 is at half mast or full mast have the device handled as in carrying out the military command of "order, arms," "shoulder arms," or "present arms." Then in compliance with the command of "fire" the devices are simultaneously thrust or struck against the pavement or other solid footing to explode the caps.

The whistle 6 may be sounded as an additional means of amusement and enthusiasm.

The foregoing being a full, clear, and exact description of the invention, what I claim, and desire to secure by Letters Patent, is—

1. A walking-cane having a hollow body, a flagstaff or banner-staff contained within said body, an opening in said body for the withdrawal of said staff, said opening having a closure in the form of a sleeve embracing said body.

2. A walking-cane having a tubular body, a flagstaff or banner-staff contained within said body, an opening in said body for the withdrawal of said staff, a closure for the opening, comprising a sleeve slidably embracing said body.

3. A walking-cane having a hollow body, the upper end of said body being formed into

a semicircular handle, said body being adapted to contain a flagstaff or banner-staff and having an opening in the handle portion for withdrawing said staff, a closure for said opening comprising a slideable sleeve mounted on said handle, said staff being adapted to be withdrawn partly or wholly through said opening and be locked in said position by said closure.

4. A walking-cane having a tubular body, a flagstaff or banner-staff contained within said body, the upper end of said body being formed into a semicircular handle and having an opening for the withdrawal of said staff, a closure for said opening, said closure being slideable upon said handle and having a slot adapted to straddle said staff as it projects outward through said opening and lock the same against movement.

5. A walking-cane having a tubular body and containing a flagstaff or banner-staff, the upper end of said body being formed into a semicircular handle and having an opening for the withdrawal of said staff for display, said opening having a closure slideable on said handle and having an open slot, said staff being adapted to be projected up through said opening for display, and be locked in said position by being straddled by said slot, said staff being provided with stops to prevent it sliding downward through said slot.

Witness my hand this 10th day of September, 1906.

GEORGE A. BEIDLER.
